UNITED STATES PATENT OFFICE.

JOHN L. OSGOOD, OF BUFFALO, NEW YORK.

DESIGN FOR A HAND-GRIP FOR A FILE OR SIMILAR ARTICLE.

58,621.

Specification for Design.

Patented Aug. 2, 1921.

Application filed April 19, 1921. Serial No. 462,716. Term of patent 14 years.

To all whom it may concern:

Be it known that I, JOHN L. OSGOOD, a citizen of the United States, residing at Buffalo, in the county of Erie and State of New York, have invented a new, original, and ornamental Design for a Hand-Grip for a File or Similar Article, of which the following is a specification, reference being had to the accompanying drawing, forming a part thereof.

In the accompanying drawings:

Figure 1 is a plan view of a hand grip for a file embodying the design.

Fig. 2 is an end view thereof.

Fig. 3 is a side view thereof.

The hand grip comprises an enlarged head, and a reduced neck which projects from the bottom of the head and is provided with a transversely elongated, narrow, longitudinal cavity, said head being substantially rectangular transversely and having a convexed top.

I claim:

The ornamental design for a hand grip for a file or similar article, substantially as shown and described.

April 16, 1921.

JOHN L. OSGOOD.
